(57) **CLAIM**

We claim the ornamental design for a cylindrical breath-enhanced nebulizer, as shown and described.

DESCRIPTION

FIG. 1 is a perspective view of the cylindrical breath-enhanced nebulizer;

FIG. 2 is a front view of the design embodiment shown in FIG. 1;

FIG. 3 is a back view of the design embodiment shown in FIG. 1;

FIG. 4 is a right side view of the design embodiment shown in FIG. 1;

FIG. 5 is a top view of the design embodiment shown in FIG. 1;

FIG. 6 is a bottom view of the design of embodiment shown in FIG. 1;

FIG. 7 is a perspective view of another aspect of the cylindrical breath-enhanced nebulizer;

FIG. 8 is a front view of the design embodiment shown in FIG. 7;

FIG. 9 is a back view of the design embodiment shown in FIG. 7;

FIG. 10 is a right side view of the design embodiment shown in FIG. 7;

FIG. 11 is a top view of the design embodiment shown in FIG. 7; and,

FIG. 12 is a bottom view of the design embodiment shown in FIG. 7.

The portion of the article in broken lines shown in FIGS. 1–12 are for illustrative purposes only and form no part of the claimed design.
